UNITED STATES PATENT OFFICE

DOUGLAS FRANKLIN FRASER, OF BOMBAY, INDIA.

BOILER-CIRCULATOR.

1,172,973.

Specification of Letters Patent. Patented Feb. 22, 1916.

Application filed June 26, 1914. Serial No. 847,444.

To all whom it may concern:

Be it known that I, DOUGLAS FRANKLIN FRASER, subject of the Emperor of India, residing in Bombay, India, have invented certain new and useful Improvements in Boiler-Circulators, of which the following is a specification.

This invention relates to improvements in steam boiler circulators in which the circulating member consists of a small propeller and the shaft of the propeller passes through the bottom of the boiler and is driven from outside.

The invention comprises the combination of a nipple, surrounding the shaft and screwed through the shell of the boiler, a nut for locking said nipple and two stuffing boxes one at each end of the nipple, said shaft being actuated by steam turbine placed below the boiler.

A construction of the invention is illustrated in the annexed drawing, in which—

Figure 1 shows a part of a cross section of a marine boiler on a vertical plane. Figs. 2 and 3 illustrate details of the turbine.

The small propeller A is placed near the bottom of the boiler and is carried on the shaft B which, passing through the boiler plate G carries at its lower extremity a small steam turbine C that is operated by steam from any convenient boiler. The furnace flues are indicated by the circles H. The inside flange or nipple is screwed through the shell of the boiler from the inside on to a faced surface and locked by the nut K on the outside. Leakage is provided against by the stuffing boxes D and E and the thrust collar X, which effectually stops all leakage of water from the boiler. The turbine 40 works in the casing F which is attached to the boiler by means of the flanged collar I which is recessed to accommodate the nut K. This flanged collar is bell mouthed and faced to receive the corresponding flange of the turbine casing F.

The turbine is constructed as shown in Figs. 2 and 3, in which two threads to the inch (for example) are cut on the rotor. These threads bear on the inside of the turbine casing but the blades are clear of the

casing and arranged in the grooves formed by the threads as shown in Fig. 2. Steam is admitted at the port Y (Fig. 2) and exhausts at the lower end of the thread, these ports being at a distance apart of approximately half the circumference of the turbine casing. The blades are flat and are inserted in slots in the threads, which slots are cut in the direction of rotation and at about 40° to a radius passing through the top of the slot. The inlet port is made tangential to the casing.

The exhaust pipe preferably discharges into the condenser. Thus an active circulation of water may be secured in all parts of an internally-fired boiler. The turbine may have a connection with a donkey boiler so as to start circulation as soon as the fires of the main boilers are lighted, after which it may be supplied from the latter. One or more circulators may be fitted to any one boiler.

What I claim as my invention and desire to secure by Letters Patent is:—

1. In a water circulator for boilers having a shaft passing through the bottom of the boiler and a rotary propeller on the shaft and inside the boiler, the combination of a nipple surrounding the shaft and having a threaded portion which is screwed through the shell of the boiler and projects exteriorly thereof, a nut screwed upon the exteriorly projecting threaded portion of the nipple and locking said nipple in position, a flanged collar bolted to the boiler and having a recess within which the said locking nut is arranged, and two stuffing boxes one at each end of the nipple, and means for actuating the shaft.

2. In a water circulator for boilers having a shaft passing through the bottom of the boiler and a rotary propeller on the shaft and inside the boiler, the combination of a nipple surrounding the shaft and having a threaded portion which is screwed through the shell of the boiler and projects exteriorly thereof, a nut screwed upon the exteriorly projecting threaded portion of the nipple and locking said nipple in position, a flanged collar bolted to the boiler and having a recess within which the said locking

nut is arranged, said collar having a flared mouth, a casing bolted to the said flared mouth of the collar, two stuffing boxes one at each end of the nipple, and a turbine arranged within the said casing and engaging the lower end of the shaft for actuating the latter.

In testimony whereof I have signed my name to this specification in the presence of two subscribing witnesses.

DOUGLAS FRANKLIN FRASER.
